Patented Nov. 5, 1968

212,654

EXTENDABLE WATER BORNE LOADING PLAT- FORM CONVERTIBLE TO LAND USE

Bernard S. Sain, 6A Creston Ave.,
Union, N.J. 07083

Filed Sept. 19, 1967, Ser. No. 8,657

Term of patent 14 years

(Cl. D71—1)

FIG. 1

FIG. 2

FIG. 3

FIG. 4

FIG. 5

FIGURE 1 is a perspective view of an extendable water borne loading platform convertible to land use, in the extended position, showing my new design;

FIGURE 2 is a top plan view thereof in the collapsed position;

FIGURE 3 is a side elevational view thereof in the collapsed position;

FIGURE 4 is a bottom view thereof in the collapsed position; and

FIGURE 5 is an end elevational view thereof in the collapsed position.

I claim:

The ornamental design for an extendable water borne loading platform convertible to land use, as shown.
